(57) **CLAIM**

The ornamental design for a serving tray, as shown and described.

DESCRIPTION

FIG. 1 is a front perspective view of a serving tray;
FIG. 2 is a front elevation view of the serving tray of FIG. 1;

FIG. 3 is a rear elevation view of the serving tray of FIG. 1;
FIG. 4 is a right side view of the serving tray of FIG. 1;
FIG. 5 is a left side view of the serving tray of FIG. 1;
FIG. 6 is a top view of the serving tray of FIG. 1; and,
FIG. 7 is a bottom view of the serving tray of FIG. 1.
The broken lines represent structure or features that form no part of the claimed design.
